COMBINED BUMPER, GRILLE AND LAMP UNIT FOR AN AUTOMOBILE

Fred L. Hudson, Jr., Fayetteville, N.Y., assignor to Chrysler Corporation, Highland Park, Mich., a corporation of Delaware

Application August 13, 1959, Serial No. 57,169

Term of patent 7 years

(Cl. D14—18)

Fig. 1 is a front view of a combined bumper, grille and lamp unit for an automobile embodying my new design;

Fig. 2 is a top plan view thereof;

Fig. 3 is a side elevational view thereof;

Figs. 4, 5 and 6 are sectional views taken on the lines 4—4, 5—5 and 6—6 of Fig. 1; and

Fig. 7 is a sectional view taken on the line 7—7 of Fig. 2.

I claim:

The ornamental design for a combined bumper, grille and lamp unit for an automobile, substantially as shown.
